FOLIAGE TRIMMER

Gustav H. Sudmeier, 13728 S. Normandy,
Gardena, Calif. 90249

Filed Aug. 10, 1966, Ser. No. 3,406

Term of patent 14 years

(Cl. D40—1)

The dominant features of my design reside in the portions shown in full lines.

I claim:

The ornamental design for a foliage trimmer, substantially as shown and described.
